UNITED STATES PATENT OFFICE.

EBENEZER HILL, OF SOUTH NORWALK, CONNECTICUT.

AIR-COMPRESSOR.

SPECIFICATION forming part of Letters Patent No. 678,487, dated July 16, 1901.

Application filed April 19, 1901. Serial No. 56,584 (No model.)

To all whom it may concern:

Be it known that I, EBENEZER HILL, a citizen of the United States, residing at South Norwalk, in the county of Fairfield and State 5 of Connecticut, have invented certain new and useful Improvements in Air-Compressors, of which the following is a specification.

This invention relates to the means provided for keeping down the temperature of 10 air or gas being compressed, and while it is particularly applicable to three-stage compressors it may be adapted to single and two stage compressors.

The object of the invention is to so arrange 15 the ducts that the air or gas in the chamber on the inactive side of a compressing-piston is obliged to flow through a cooler before reaching the chamber on the active side of a piston, thus insuring the cooling of all of the 20 air or gas.

The embodiment of the invention that is illustrated has three compression-cylinders with common valves and pistons, the first or largest being double acting and the second 25 or middle and the third or smallest being single acting, with a duct leading from the chambers on the active sides of the first piston through a cooler to the chamber on the active side of the second piston, a duct leading 30 from the chamber on the active side of the second piston through a cooler to the chamber on the active side of the third piston, and a duct leading from the chamber between the inactive sides of the second and third 35 pistons and communicating with the duct from the first cylinder before it passes through its cooler, as more particularly hereinafter described, and pointed out in the claims.

Figure 1 of the drawings is a side elevation showing the essential features of a three-stage compressor with parts broken away to expose the mechanism. Fig. 2 is an end elevation of the same compressor; and Fig. 3 is a view showing a single cylinder, piston, and 45 cooler with a duct leading from the chamber on the inactive side of the piston and communicating with the cooling-duct before it passes through the cooler.

The steam-cylinder 1 is of ordinary construction and has the usual valves. The steam-piston 2 is connected by a rod 3 with a piston 4 in the first compression-cylinder 5.

The usual valves are so arranged that air or gas will enter this cylinder through the inlet-pipe 6 and be expelled through the outlet-pipe 7 at each stroke of the piston. This outlet-pipe passes through a cooler 8 of ordinary construction and is connected with the chamber on the active side of the second compression-cylinder 9. This second cylinder 55 has common valves so arranged that air or gas which enters is expelled only on the back stroke of the compression-piston 10, that by a rod 11 is connected with the first compression-piston. A pipe 12 passes from the 60 chamber on the active side of the second compression-piston through an ordinary cooler 13 to the chamber on the active side of the compression-piston 14 in the third compression-cylinder 15. Air or gas is expelled from 70 the third cylinder through the outlet-pipe 16. The third compression-piston is connected by a rod 17 with the second compression-piston. The second compression-cylinder and the third compression-cylinder communicate, 75 and the active chambers are on opposite sides of the pistons in these cylinders—that is, air or gas is compressed by the second piston on the back stroke and by the third piston on the forward stroke. The chamber 18 between 80 these pistons is inactive. A pipe 19 leads from the passage 20, that communicates with the chamber 18 between the inactive sides of the second and third pistons, to the pipe that communicates with the first cylinder before 85 the latter pipe passes through the cooler 8, that cools the air or gas after it has been compressed in the first cylinder and is being forced to the second cylinder.

The compression-cylinders have common 90 water-jackets and an ordinary circulating system 21, connecting the cylinder-jackets and the coolers with the source of the cooling fluid. By these means air or gas is cooled in the cylinders while under compression and 95 while flowing from the chamber on the active side of one piston to the chamber on the active side of the next piston. The air or gas that ebbs and flows out of and into the chamber between the pistons is also cooled before 100 it can pass to the chamber on the active side of a piston and commingle with the air or gas to be compressed by that piston, for it must pass through a cooler.

Subjecting all of the air or gas both in the chambers on the inactive sides of the pistons as well as in the chambers on the active sides of the pistons to the effect of the cooling fluid 5 keeps the temperature down to such an extent that it is not necessary to spray the cylinders and boxes containing the packings to prevent them from becoming overheated.

The invention is not limited to a three-stage compressor. The first compression-cylinder could be omitted, if desired, and, as shown in Fig. 3, the invention could be applied to a single-stage compressor. In this latter form the single-acting piston 22 compresses air or gas in the cylinder 23 on the back stroke. The inlet-pipe 25 and outlet-pipe 26 communicate with the chamber 24. The end of the cylinder is closed, so as to prevent the escape of air or gas that might leak 20 past the piston into the chamber 27 on the inactive side of the piston, and this chamber is by a pipe 28 connected with the cooling-duct before it passes through the cooler 29, so that air or gas that surges into and out of 25 the chamber on the inactive side of the piston will be obliged to flow through the cooler before commingling with the air or gas that is compressed in the cylinder.

The coolers may be any common construction, and if more than one is used may be arranged one above the other, as shown in Fig. 1, or side by side, as is common with many compressors of this nature. The cylinders shown are arranged tandem, although they 35 might be arranged parallel with one another.

The essential feature of this invention is the connecting of the chamber on the inactive side of a compressing-piston with a duct before that duct passes through the cooler that 40 keeps down the temperature of the air or gas being compressed.

The employment of this invention results in lowering the temperature of the air or gas under compression, and consequently decreasing 45 the temperature of the compressor parts. This increases the efficiency of the compressor and reduces the wear of the parts.

I claim as my invention—

1. An air-compressor having a cylinder with 50 a single-acting piston, a cooler, a duct con-

nected with the chamber on the active side of the piston and extending through the cooler, and a duct connecting the chamber on the inactive side of the piston with the cooler-duct before it passes through the cooler, substantially as specified. 55

2. An air-compressor having cylinders with two single-acting pistons so arranged that the chambers on the inactive sides of the pistons communicate with each other, a cooler, a duct connected with the chamber on the active side of one of the pistons and extending through the cooler, and a duct connecting the communicating chambers on the inactive sides of the pistons with the cooler-duct before it passes 65 through the cooler, substantially as specified. 65

3. An air-compressor having a plural number of cylinders with pistons, coolers, ducts connected with the chambers on the active sides of the pistons and extending through 70 the coolers, and a duct connecting the chambers on the inactive sides of the pistons with a cooler-duct before it passes through a cooler, substantially as specified.

4. An air-compressor having cylinders with 75 a double-acting and two single-acting pistons, a cooler, a duct connecting the chambers on the active sides of the single-acting pistons and extending through the cooler, and a duct leading from the chamber on the inactive sides 80 of the single-acting pistons to the cooler-duct before it passes through the cooler, substantially as specified.

5. An air-compressor having cylinders with 85 a double-acting and two single-acting pistons, a cooler, a duct connecting the chambers on the active sides of the first piston with the chamber on the active side of the second piston and extending through the cooler, a duct connecting the chamber on the active side of 90 the second piston with the chamber on the active side of the third piston, and a duct leading from the chamber between the second and third pistons to a cooler-duct before it passes through a cooler, substantially as specified. 95
